AUTOMATIC DUMPER FOR CARRIER SYSTEMS

Lester C. Smith, West Hartford, Conn., assignor to The Spencer Turbine Company, Hartford, Conn., a corporation of Connecticut

Application May 17, 1934, Serial No. 726,129

15 Claims. (Cl. 302—59)

My invention relates to that class of apparatus which is used in connection with pneumatic conveyors to receive and discharge material delivered thereto by the conveyor, and an object 5 of my invention, among others, is the production of an apparatus of this sort that shall be particularly efficient in its method of operation.

One form of a machine embodying my invention and in the construction and use of which 10 the objects herein set out, as well as others, may be attained is illustrated in the accompanying drawings in which—

Figure 1 is a top view of my improved dumper. Figure 2 is a view in side elevation of the same.

15 Figure 3 is a view similar to Fig. 2 but looking from a point at right angles to the point of view of Fig. 2.

Figure 4 is a view in elevation on enlarged scale of the collector constituting a part of my 20 improved dumper.

Figure 5 is a top view of the same.

Figure 6 is a view in vertical section through the collector.

It is common practice at the present time to 25 remove material from one place and deposit it in another location, by the use of pneumatic apparatus, and my improved device herein illustrated and described enables this operation to be accomplished in a most satisfactory manner by permitting the pneumatic apparatus to function to 30 its fullest extent, the material being deposited in a collector from which it is periodically automatically discharged. In the accompanying drawings the numeral 10 denotes a case or shell 35 constituting a receiver having an inlet 11 to which a conveying tube is attached for delivery of material into the shell, said shell also having an outlet 12 connected with any suitable vacuum producing apparatus which operates to create a 40 partial vacuum within the shell 10 in a manner that will be readily understood. The interior of the shell may be constructed in any suitable manner to separate the conveyed material from the air, this constituting no part of my invention 45 and a description of its details therefore being omitted herein except to state that a separator 13 of fabric or other suitable material is shown in dotted lines in Fig. 2. The shell may be supported in any suitable manner as upon legs 50 14 and its lower end is preferably tapered to form a hopper 15 into which the material drops from the shell 10.

An interior collector 16 is located at the outlet 55 from the hopper 15 to receive material discharged from the latter, this collector having an inclined

bottom 17 and a trap door 18 opening into an anterior collector 19 within which the interior collector is located.

The edge of the discharge opening from the collector 16 is inclined from the vertical, and as 5 shown in Fig. 6 of the drawings, so that matter accumulated within the chamber in said collector will be quite freely discharged therefrom into the anterior collector 19. The trap door is secured to a shaft 20 mounted in bearings in the 10 walls of the anterior collector 19, said shaft having a weighted arm 21 secured to its end outside of the collector 19, the weight acting to open the door when the latter is relieved from the influence of the vacuum within the shell 10. 15

The anterior collector 19 has a trap door 22 arranged similarly to the door 18, the edge of the opening against which the door 22 rests being inclined as above described, and the edges of the openings for both of the doors 18 and 22 are suitably packed to prevent the entrance of air under the influence of the vacuum within the collectors. The shaft 23 of the door 22 has a weighted arm 24 rotatably mounted thereon and a door closing cam 25 is secured to the arm 24 in position 25 to make contact with a weighted pad 26 at the end of the arm 21, and as shown in Fig. 2 of the drawings. A valve operating arm 27 is also secured to the arm 24 for a purpose to be hereinafter described. Pins 28 and 29 project from 30 a collar secured to the shaft 23 and are spaced apart to receive a pin 30 projecting from the arm 24, the pin 30 having a limited movement independently of the pins 28 and 29 for a purpose to be hereinafter described. 35

The arm 27 is connected by a rod 31 with an extension from a valve 32 which controls an opening through a nipple 33 into the top of the collector 19, this valve constituting a bleeder for the chamber within said collector. This valve 40 is pivotally mounted on a bracket 34 secured to the top of the collector 19 and said valve has an arm 35 extending therefrom and connected by a rod 36 with a valve 37 which controls air flow through a tube 38 extending from the chamber 45 within the collector 19 into the chamber within the shell 10.

A trap door actuating rod 39 is secured at one end to the arm 24 and at its opposite end to an extension from a bellows actuator 40 secured to 50 the under side of a plate 41 attached to a shelf 42 secured to and projecting from the side of the shell 10, and as shown in Figs. 1 and 3 of the drawings. The bellows of which said actuator comprises a part is connected by a tube 43 with 55

the interior of the shell 10, as by a connection to the tube 38, and a valve 44 controls the pressure within the tube 43, being connected by a rod 45 with a valve actuating lever 46 pivotally attached at its lower end to the shelf 42. The lever 46 is connected with the core of a solenoid 47 mounted on the shelf 42 and having line wires 48-49 connected therewith.

A timing motor 50 of any suitable type, electrical or mechanical, is mounted on the shelf 42 and is connected with a controller which it operates at a comparatively low speed by means of reduction gearing in a gear case 51, said gearing including a shaft and said controller comprising an insulated disk 52 secured to said shaft and bearing a brush 53 adapted to sweep a contact 54 mounted on an insulated base and connected by a wire 55 with a relay 56 connected by a wire 57 with the line wire 48. The relay 56 when energized operates a switch 58 to close the line wire 48. The brush 53 is grounded as at 59 and the wire 49 is grounded as at 60.

The valve 44 is a three-way valve which in one position opens the tube 43 to the atmosphere and in another position opens said tube through the tube 38 to the interior of the shell 10.

When the apparatus is operated to draw material into the shell 10, the trap door 18 is open, as shown in dotted lines in Fig. 2, the valve 32 is closed, and the valve 37 opens communication between the chamber in the collector 19 and the interior of the case 10.

The three-way valve 44 is in position to open the tube 43 to the atmosphere so that the bellows actuator 40 is expanded as shown in Fig. 3 and the vacuum produced in the chamber in the collector 19 maintains the trap door 22 in its closed position. Communication through the pipe 38 between the chamber in the collector 19 and the chamber in the shell 10 equalizes the vacuum on both sides of the door 18 permitting it to remain open. This is the position of the parts when the electric circuit is broken by the controller embodying the disk 52, said disk, however, being rotated by the timing motor 50.

When the brush 53 touches the contact 54 a circuit is established through the wire 49, grounds 60 and 59, brush 53, contact 54, wire 55, relay 56 and wire 48. Energizing of the relay closes the switch blade 58 thereby establishing a circuit through the solenoid 47. The core of the solenoid being drawn inwardly the valve actuating lever 46 is operated to turn the three-way valve 44 thereby establishing communication through the tube 43 from the actuator 40 to the interior of the shell 10, which creates a partial vacuum in the bellows comprising said actuator to collapse it, and this draws the rod 39 upwardly, rotates the arm 24 on the shaft 23. This movement of the arm 24 independently of said shaft presses the cam 25 into contact with the pad 26, to close the trap door 18. At the same time the arm 27 is operated to open the valve 32 thereby relieving the vacuum in the chamber in the collector 19, the valve 37 being simultaneously operated to cut off the vacuum through the pipe 38. Just after the door 18 has been closed and the valve 32 has been opened the pin 30 strikes the pin 29 thereby rotating the shaft 23 to open the door 22 and permit the contents of the chamber in the collector 19 to be discharged. Immediately upon release of the vacuum in the chamber in the collector 19 by the opening of the valve 32 the partial vacuum within the shell 10 and the

interior collector 16 causes the door 18 to remain closed.

As the brush 53 leaves the contact 54 the electric circuit is opened at all points, the switch 58 opening automatically and a spring 61 acting on the core of the solenoid 47 pushes the core outwardly, thereby operating the three-way valve 44 to open the tube 43 to the atmosphere. This relieves the partial vacuum in the controller which includes the actuator 40 and the weighted arm 24 expands said controller and as the pin 30 comes into contact with the pin 28 the door 22 is closed and pressure of the cam 25 on the door 18 is relieved so that the latter may open. This contact of the pin 30 with the pin 28 also closes the valve 32 and this action also operates the valve 37 to open the tube 38 for communication between the chamber in the shell 10 and in the collector 19, thereby creating the same vacuum in the latter chamber as in the shell and permitting the door 18 to open. The parts are now in the position for a repetition of the action just described.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. A dumping apparatus including a shell having an inlet for supply of material thereto and an outlet for connection to a vacuum producing apparatus, an anterior collector at the bottom of the shell, an interior collector relatively located with respect to said anterior collector, a trap door for each of said collectors, a tubular connection between the chamber in the anterior collector and the chamber in the shell, and mechanism connected with the door of the anterior collector and automatically actuated by pressure within the shell for opening said last mentioned door.

2. A dumping apparatus including a shell having an inlet for supply of material thereto and an outlet for connection to a vacuum producing apparatus, an anterior collector at the bottom of the shell, a trap door for said collector, an interior collector relatively located with respect to said anterior collector, a trap door for said interior collector, yielding means for opening said door to the interior collector, a tubular connection between the chamber in the anterior collector and the chamber in the shell, and mechanism connected with the door of the anterior collector and automatically actuated by pressure within the shell for opening said last mentioned door.

3. A dumping apparatus including a shell having an inlet for supply of material thereto and an outlet for connection to a vacuum producing apparatus, an anterior collector at the bottom of the shell, a trap door for said collector, an interior collector relatively located with respect to said anterior collector, a trap door for said interior collector, a weighted device connected with said last mentioned door to open it, a tubular connection between the chamber in the anterior collector and the chamber in the shell, and mechanism connected with the door of the anterior collector and automatically actuated by pressure within the shell for opening said last mentioned door.

4. A dumping apparatus including a shell having an inlet for supply of material thereto and an outlet for connection to a vacuum producing apparatus, an anterior collector at the bottom 5 of the shell, an interior collector relatively located with respect to said anterior collector, a trap door for each of said collectors, a weighted device connected with the door of the interior collector to open it, an arm attached to the door 10 of the anterior collector for opening it, a connection between the door of the anterior collector and the door of the interior collector to close the latter, and a tubular connection between the chamber in the anterior collector and 15 the chamber in said shell.

5. A dumping apparatus including a shell having an inlet for supply of material thereto and an outlet for connection to a vacuum producing apparatus, an anterior collector at the bottom 20 of the shell, an interior collector relatively located with respect to said anterior collector, a trap door for each of said collectors, a tubular connection between the chamber in the anterior collector and the chamber in the shell, means 25 connected with the door of the anterior collector and automatically actuated by pressure within the shell for opening said last mentioned door, and time operated mechanism connected with said door opening means for regulating its operation. 30

6. A dumping apparatus including a shell having an inlet for supply of material thereto and an outlet for connection to a vacuum producing apparatus, an anterior collector at the bottom 35 of the shell, an interior collector relatively located with respect to said anterior collector, a trap door for each of said collectors, a tubular connection between the chamber in the anterior collector and the chamber in the shell, means 40 loosely connected with the door of the anterior collector to open it, said means having a limited movement independently of said door, and a connection between said door opening means and the door to the interior collector for 45 operation of the latter independently of the former.

7. A dumping apparatus including a shell having an inlet for supply of material thereto and an outlet for connection to a vacuum producing 50 apparatus, an anterior collector at the bottom of the shell, an interior collector relatively located with respect to said anterior collector, a trap door for each of said collectors, a tubular connection between the chamber in the anterior 55 collector and the chamber in the shell, means connected with the door of the anterior collector and automatically actuated by pressure within the shell for opening said last mentioned door, and a valve connected with said door opening 60 means to admit air to the chamber in the anterior collector.

8. A dumping apparatus including a shell having an inlet for supply of material thereto and an outlet for connection to a vacuum producing 65 apparatus, an anterior collector at the bottom of the shell, an interior collector relatively located with respect to said anterior collector, a trap door for each of said collectors, a tubular connection between the chamber in the anterior 70 collector and the chamber in the shell, means for admitting air to the chamber in the anterior collector, means loosely connected with the door of the anterior collector for opening it, said means having a limited movement independently of said door, a connection between said 75

door opening means and the door of the interior collector for operation of the latter independently of the former, and a connection between said door opening means and said air admitting means for operation of the latter before opening movement of said door. 5

9. A dumping apparatus including a shell having an inlet for supply of material thereto and an outlet for connection to a vacuum producing apparatus, an anterior collector at the bottom 10 of the shell, an interior collector relatively located with respect to said anterior collector, trap doors for each of said collectors, a tubular connection between the chamber in the anterior collector and the chamber in the shell, a shaft 15 for the door of the anterior collector, a door opening arm pivotally mounted on said shaft, means rigid with said shaft for engagement by said door opening arm after the beginning of movement of the latter to open said door, and a 20 connection between said door opening arm and a device closing an opening into the chamber in said anterior collector for operation of said device by said arm. 25

10. A dumping apparatus including a shell having an inlet for supply of material thereto and an outlet for connection to a vacuum producing apparatus, an anterior collector at the bottom of the shell, an interior collector relatively located with respect to said anterior collector, a trap 30 door for each of said collectors, a tubular connection between the chamber in the anterior collector and the chamber in the shell, means connected with the door of the anterior collector for opening it, pressure actuated means connected 35 with the chamber in said shell and with said door opening means for operation of the latter by pressure within the shell, and means for controlling pressure within said pressure actuated means. 40

11. A dumping apparatus including a shell having an inlet for supply of material thereto and an outlet for connection to a vacuum producing apparatus, an anterior collector at the bottom of the shell, an interior collector relatively located with respect to said anterior collector, a trap door 45 for each of said collectors, a tubular connection between the chamber in the anterior collector and the chamber in the shell, means connected with the door of the anterior collector for opening it, a bellows actuator connected with said door opening means, a tubular connection between said bellows actuator and the chamber within the shell, and a valve for controlling said last mentioned tubular connection. 50

12. A dumping apparatus including a shell having an inlet for supply of material thereto and an outlet for connection to a vacuum producing apparatus, an anterior collector at the bottom of the shell, an interior collector relatively located with respect to the anterior collector, trap doors 60 for each of said collectors, a tubular connection between the chamber in the anterior collector and the chamber in the shell, means connected with the door of the anterior collector for opening it, a bellows actuator operatively connected with said door opening means, a tubular connection between said bellows actuator and the chamber in the shell, a valve to control said connection, and a time actuated device connected with said valve for operating it. 65

13. A dumping apparatus including a shell having an inlet for supply of material thereto and an outlet for connection to a vacuum producing apparatus, an anterior collector at the bottom of the shell, an interior collector relatively located 70 75

with respect to said anterior collector, a trap door for each of said collectors, a tubular connection between the chamber in the anterior collector and the chamber in the shell, means connected with the door of the anterior collector and automatically regulated by pressure within the shell for opening said last mentioned door, a valve in said tube, and a connection between said valve and said door opening means for actuation of the former by the latter.

14. A dumping apparatus including a shell having an inlet for supply of material thereto and an outlet for connection to a vacuum producing apparatus, an anterior collector at the bottom 5 of the shell, an interior collector relatively located with respect to said anterior collector, a trap door for each of said collectors, a tubular connection between the chamber in the anterior collector and the chamber in the shell, means connected with the door of the anterior collector for 10 opening it, a valve for admitting air to the chamber in said anterior collector, an operative connection between said valve and said door opening

means, a valve in said tubular connection, and a connection between said valves for operation of one by the other.

15. A dumping apparatus including a shell having an inlet for supply of material thereto and an outlet for connection to a vacuum producing apparatus, an anterior collector at the bottom 5 of the shell, an interior collector relatively located with respect to said anterior collector, a trap door for each of said collectors, a tubular connection 10 between the chamber in the anterior collector and the chamber in the shell, a valve in said tubular connection, a connection between said door opening means and said valve for operation of the latter by the former, a pressure actuator 15 operatively connected with said door opening means, a tubular connection between said actuator and the chamber within the shell, a valve for controlling said last mentioned tubular connection and arranged to open said connection to the 20 air or to said pressure actuator, and time actuated means for operating said valve.

LESTER C. SMITH.
